CLAIM

The ornamental design for a jewelry setting, as shown and described.

DESCRIPTION

FIG. 1 is a top view of a first embodiment of a jewelry setting;

FIG. 2 is a perspective view of the jewelry setting of FIG. 1;

FIG. 3 is another perspective view of the jewelry setting of FIG. 1;

FIG. 4 is a side view of the jewelry setting of FIG. 1;

FIG. 5 is a perspective view of the jewelry setting of FIG. 1 in a pendant;

FIG. 6 is a top view of the jewelry setting of FIG. 5;

FIG. 7 is a perspective view of the jewelry setting of FIG. 1 in an earring;

FIG. 8 is a side view of the jewelry setting of FIG. 7;

FIG. 9 is a top view of the jewelry setting in an earring;

FIG. 10 is a side view of the jewelry setting of FIG. 9;

FIG. 11 is a top view of the jewelry setting in a ring; and, FIG. 12 is a top view of the jewelry setting in another ring.

The broken lines are provided for illustrative purpose only and form no part of the claimed design.
